UNITED STATES PATENT OFFICE.

FRANK HASKELL, OF WESTBROOK, MAINE.

MACHINE FOR SPOOLING YARN.

SPECIFICATION forming part of Letters Patent No. 396,816, dated January 29, 1889.

Application filed August 29, 1887. Serial No. 248,126. (No model.)

To all whom it may concern:

Be it known that I, FRANK HASKELL, of Westbrook, in the county of Cumberland and State of Maine, have invented certain new and useful Improvements in Machines for Spooling Yarn; and I do hereby declare that the following is a full, clear, and exact description of the invention, that will enable others skilled in the art to which it appertains to make and use the same, reference being had to the accompanying drawings, forming a part of this specification, in which—

Figure 1 is a perspective view of the machine; Fig. 2, a side elevation of part of the machine; Fig. 3, an end view of the same; Fig. 4, a top plan of the rocker; Fig. 5, a longitudinal section of a part of the machine, showing in top plan the plate through which the drop-wires pass; Fig. 6, a cross-section through the line $\mu\mu$ of Fig. 5; Fig. 7, a side elevation of one of the drop-wires; Fig. 8, a section through the plates holding the drop-wires; Fig. 9, a top plan of the machine with the plates $i' i'$ and the parts above them removed. Fig. 10 is a detail of the parts beneath the frame; Fig. 11, a detail of pulley v and shaft c ; Fig. 12, a detail in side elevation of the gear 6 ; Fig. 13, a detail showing in top plan the pulley v and shaft c .

My invention relates to spooling devices, and its object is, particularly, to provide improved means for instantly stopping the spooling device when a thread breaks or any such accident occurs.

The machine shown in the drawings consists of a mechanism for rotating the spools, means for guiding the threads, and a stop-motion.

A A represent the frame of the machine. Upon one side of this frame, in suitable journals, is the shaft B, having at one end the fixed pulley E and the loose pulley D, by the former of which and the belt F power is imparted to the machine. Upon the shaft B, at regular intervals, are fixed the pulleys or rollers H H. Upon a part of the frame over the rollers H H are placed the bearings J J, on which are placed the spools I I. These bearings should be so constructed and located that the sides of the spools, whatever their size, may rest upon the rollers H H. The other end of the shaft B may be provided with the beveled gear a , which matches a beveled gear b , on the shaft d, which extends

across the end of the frame A. The other end 55 of the shaft d has the beveled gear e, matching the beveled gear f on the shaft c, which extends along the opposite side of the frame A, and, like the shaft B, is provided with the rollers H H, surmounted with like provision 60 for the spools I I.

The device for guiding the threads consists of the drop-wires $h h$ and the guide-wires K K, with means for moving the latter to and fro. The guide-wires K K are fixed at regular intervals, one being opposite each of the spools I I, in the rods $l l$, which, at one end of the machine, slide in suitable grooves, and at the other end are supported by and connected with the rods $m m$, which are pivoted to the lever n .

The lever n is rigidly fixed upon the shaft o, which is supported by the bearing I⁴, (see Fig. 1,) and at the lower end has rigidly fixed thereto the lever p. The lever p at the other 75 end is pivotally connected to the rod q, the other end of which is pivotally connected to the lever 4, which is pivoted at one end to the frame A and at the other end terminates in the segmental gear r, which matches the 80 gear s on the shaft 5. The shaft 5 also carries the gear 6, which is provided with gears s^2 and s^3 upon its upper and lower surfaces, respectively. The gear 6 is not a complete circle, but has an opening, in which, midway 85 between the sides of this opening, is an arm, projected from the center of the gear. (See Fig. 10.) To the end of this projecting arm is rigidly attached the piece 15, which is of the shape shown Fig. 12, the concaved sides 90 of the piece 15 being respectively equally distant from the side of the opening in the gear which is nearest it. The front of the piece 15 should be concentric with the center of the gear and an arc of the same circle as the rim of the gear, the spaces between the curved side of the piece 15 and the edge of the opening in the gear being but slightly larger than the shaft u. The gears s^2 and s^3 alternately match the pinion t on the shaft u, 95

which is so journaled as to admit of vertical motion to the extent of the thickness of the gear 6. At the other end the shaft u is provided with the pulley v, which by belt w is connected with a pulley or groove, 8, on the 100 shaft c.

The parts or mechanism of the stop-motion may be described as follows: The drop-wires

h h should be equal in number to the spools I I. They are preferably of the shape shown in Fig. 7, and slide in slots in the plates *i i'*, the plate *i* having one circular opening, through which the longer arm of the wire slides, and the lower plate, *i'*, two circular holes or slots, through which both the long and short arms slide. I prefer that they should be arranged at regular intervals and in the order shown in Fig. 5. The plates *i i'* are placed on suitable standards on the frame A in preferably a central position between the spools I I. Beneath the plate *i'* is a plate, *i''*, having a continuous opening, 9, through which the drop-wires may pass when the ring rests upon the plate *i*. Beneath the plate *i''* is hung the rocker *a'*. It is in general outline of a figure similar to the outline formed by the holes or slots through which the drop-wires *h h* play in the plate *i*, but slightly smaller, and should be so placed as to be equidistant from the sides of the opening 9.

The upper part of the rocker consists of a frame, which, as has been stated, is similar in figure to the outline of the drop-wire slots. This frame is supported by arms which at their lower ends are fixed to a shaft, *z*, which is journaled at either end in proper bearings. Above this shaft and fixed to it is a short rod. Upon this rod *z'* is placed the rod *b'*, provided with a semicircular bend, which receives the rod *z* when in its ordinary position under the rod *b'*, to which is rigidly connected the rod *d'*, (passing through the guide 10,) which is in turn pivotally connected to the rod *e'*, which is pivoted eccentrically to the gear *f*, which is supported upon a shaft, *z''*, at the end of the frame. (See Fig. 9.) The gear *f'* matches the pinion *h'* on the shaft *d*.

Directly over the rod *d'* is the rod *k'*, passing nearly at right angles to the former and pivoted at about midway of its length to the frame of the machine. Under the rod *k'* is the piece *l'*, having the catch *m'*. The inner end of the rod *k'* is connected by means of the extensible adjustable link *3''* to the lever *n'*, which is in turn pivoted to the side of the standard L and terminates above on the friction-pad *o'*. The outer end of the rod *k'* is pivotally connected to the rod *p'*, which (being held in supporting-guides attached to the frame) is pivotally connected to the lever *q'* at the end of the frame. The lever *q'* at the other end is pivotally connected to the rod *r'*, which passes through a guide, 1. The lever *q'* is itself pivoted at about midway of its length upon a support on the frame. Between the guide 1 and the stop 2, which is fixed to the rod, is the coil-spring 3. (See Fig. 9.) Over the plates *i i'*, and on either side of the same, are placed standards L L, having at equal heights the brackets N N, with slot S.

The operation of the machine in spooling is similar to that of other like machines. The beam containing the chain is placed upon the brackets, and tension, if desired, obtained by

the use of the lever 12, with weight 14. The ends of the yarns are unwound for a short distance and carried downward through the rings of the drop-wires *h h*, those destined for the spools on one side being separated from the others by the roller 11. After being carried through the rings the respective yarns are passed through the guide-wires and the ends twisted or wound upon the spools by hand. The lever *k'* being placed in the catch *m'*, the belt F is shipped from the loose pulley D to the fixed pulley E, and the machine started. The action of the device for guiding the threads evenly upon the spools is readily seen. Power transmitted by the belt *w* to the shaft *u* causes, through the mechanism shown in Fig. 10, the alternate motion of the rods *l l*, which carry the guide-wires. If a yarn breaks or a spool ceases to rotate, the tension of the thread is slackened and permits the drop-wire *h*, through which the thread passes, to fall until the ring rests upon the plate *i*, the lower end being thus carried to a point below the upper surface of the rocker *a'*, the further movement of which is thus prevented. The stopping of the rocker so effected causes the bent part of the rod *b'* to be forced from its position on the rocker and the straight part of the rod to be carried over the rocker, thus lifting the rod against the rod *k'*, which is laterally thrown from the catch *m'*, allowing the spring 3 to act on the rod *r'*, which moves the lever *q'* on its pivot and thus slides the rod *p'* longitudinally—a movement of the rod *r'* which carries the belt F from the pulley to the loose pulley. The machine is thus immediately stopped until the yarn is tied or other change made. The movement of the lever *k'* forces the friction-pad *o'* against the side of the beam and stops its revolution at the same instant that the machine is stopped.

The construction of the machine in relation to the levers *p'*, *q'*, and *r'* may of course be varied. The shipper may be attached to the rod *p'* and the spring applied to it, the pulleys D and E being placed on the shaft *c* in reverse order to that in which they are applied to the shaft B, as illustrated in Fig. 9 of the drawings, and the use of the lever *q'* and rod *r'* avoided. The spring should be applied in such manner as to force the rod *p'* toward the pulleys D and E.

What I claim is—

The combination of the drop-wires *h h*, the slotted plates *i* and *i'*, plate *i''*, having the opening, as described, the rocker *a'*, levers *b'* and *d'*, and guide 10, rod *e'*, gears *f'* and *h'*, catch *m'*, lever *k'*, rod *p'*, lever *q'*, rod *r'*, spring 3, and shipper-guide *s'*, substantially as described.

In testimony that I claim the foregoing I have hereunto set my hand this 26th day of August, 1887.

Witnesses: FRANK HASKELL.
GEO. E. BIRD,
BENJ. F. ANDREWS.
